US0D1006149S

(12) **United States Design Patent** (10) **Patent No.:** **US D1,006,149 S**
Carruthers (45) **Date of Patent:** **** Nov. 28, 2023**

(54) **HANDLE FOR CLIMBING EXERCISE MACHINE**

(71) Applicant: **Nathaniel Carruthers**, Austin, TX (US)

(72) Inventor: **Nathaniel Carruthers**, Austin, TX (US)

(73) Assignee: **CLMBR1, LLC.**, Denver, CO (US)

(**) Term: **15 Years**

(21) Appl. No.: **29/776,739**

(22) Filed: **Mar. 31, 2021**

(51) LOC (14) Cl. **21-02**

(52) U.S. Cl.

USPC **D21/694**

(57) **CLAIM**

The ornamental design for a handle for a climbing exercise machine, as shown and described.

DESCRIPTION

FIG. 1 is a top perspective view of a handle for a climbing exercise machine showing my new design;

FIG. 2 is a bottom perspective view thereof;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is a bottom view thereof.

1 Claim, 7 Drawing Sheets
